UNITED STATES PATENT OFFICE

ALEXANDER I. ABRAHAMS, OF NEW YORK, N. Y.

SOUND AMPLIFIER

Application filed November 17, 1930. Serial No. 496,114.

My invention relates to a new and improved sound amplifier.

One of the objects of my invention is to provide a new and improved sound amplifying horn, which is especially adapted for outdoor use or in other locations where the horn is affected by moisture.

Another object of my invention is to provide a sound amplifying horn which can be easily and cheaply constructed and which will not be affected by moisture.

Another object of my invention is to provide a sound amplifying horn which shall have a composite wall, said wall including metal or other suitable rigid material which is not affected by moisture, so that the horn will have the same resistance to moisture as an all-metal horn, without having the weight and the undesirable resonance of an all metal horn.

Other objects of my invention will be set forth in the following description and drawings which illustrate preferred embodiments thereof, it being understood that the above general statement of the object of my invention is intended merely to generally explain the same and not to limit it in any manner.

Fig. 1 is an elevation.

Fig. 2 is a central sectional view.

Fig. 3 is a sectional view on the line 3—3 of Fig. 2.

Figs. 4, 5 and 6 show modifications.

It has been known for many years that horns which were used outdoors or in other locations where moisture could attack the horns, gradually became deformed because of the effect of moisture. It has been attempted to protect horns made of paper, cloth, or the like, by means of a suitable lacquer. However, experience has shown that the lacquer always chipped off the outside of the horn, so that moisture could enter the material of the wall of the horn. In order to maintain the horn in its original shape, it has been proposed to make the horn of metal. However, a metal horn having a thin wall produces a disagreeable resonance effect, and a metal horn having a sufficiently thick wall is too heavy for practical use.

It has been suggested to make a horn for

outdoor use from specially prepared and molded fibre, but such horns have been very expensive to manufacture.

According to my invention the horn is made of a layer or layers of cloth, paper, or other suitable nonmetallic material, which must be impregnated or coated with a suitable lacquer or other material, in order to render the same waterproof. I prefer to make the wall of the horn of the cloth material shown in Abrahams Patent No. 1,501,032, although I do not wish to be limited to this particular material. In manufacturing a horn of the knit material specified in said United States Patent No. 1,501,032, a mold is used which may be made of several sections, and the material is pulled over this mold in one or more sections, and the material is suitably impregnated and baked in order to harden it and to cause it to assume its final desired shape.

In the embodiments shown in Figs. 1-3, a horn of ordinarily conventional shape is shown, it being understood that the invention is not limited to any particular shape of horn. This horn comprises a continuous outer layer of material 1 and a continuous inner layer of material 2, the layers 1 and 2 being made of cloth, paper or other suitable non-metallic material.

In this embodiment three metal sections 3, 3a and 3b are utilized to prevent the horn from being deformed by the action of moisture. These metal sections 3, 3a and 3b have the desired shape, and they can be applied to the outside of the inner layer of material 2 after said inner layer 2 has been placed upon the mold. The sections 3, 3a and 3b can be held in place by suitable adhesive, such as the impregnating material which is used for coating or impregnating the layer of material 2. The outer layer of material 1 is then applied, it being understood that this outer layer is also suitably coated or impregnated.

The use of separated metal sections makes it much more easy to manufacture the horn, and the weight of the horn is also diminished.

The horn is provided with the usual metal

end or ferrule, which is made of any suitable metal. The layers 1 and 2 extend into this ferrule 4 up to the mouth 4a thereof. The innermost metal section 3b also extends within the ferrule 4. Hence, when the horn is held in the position shown in Fig. 2, the ferrule 4 acts to shed water. The space between the metal sections 3a and 3b is bridged by an outer metal thimble 5, and this outer thimble 5 is held in position by any suitable adhesive, such as the lacquer which is used for coating or impregnating the layers 1 and 2. This lacquer may be of bakelite or varnish, or it may have any suitable composition. If desired the outer thimble 5 can be connected to the inner sections by screws, rivets, etc.

The bell of the horn is also reinforced by a ring 6 which is made of any suitable metal, this ring being shaped so as to clamp the wide end of the horn, as clearly shown in Fig. 2.

If rain falls upon the horn, it cannot penetrate the outer layer 1 intermediate the metal sections 3a and 3b, as this is prevented by the outer member 5.

In the zone between the metal members 3 and 3a, the taper of the horn is so large as to effectively shed the water. It would not be departing from the invention if an additional outer member were provided to bridge the gap between the members 3 and 3a, this outer member being similar to the member 5, which has been previously disclosed. However, this is not necessary, and the use of a single outer member is preferred. It is standard practice to make these horns of the exponential type, and experience has shown that it is not necessary to use an outer member 5 at that part of the horn which has a large taper.

As shown in Fig. 4 the three metal sections previously described may be replaced by two metal sections 7 and 7a, the constructions being otherwise the same.

As shown in Fig. 5 the metal sections previously described may be replaced by metal sections 8 and 8a, so that the bell end of the horn, which has a large taper, is not provided with any rigid reinforcing members. The construction is otherwise the same.

As shown in Fig. 6 the intermediate metal sections previously described may be replaced by outer metal sections 9 and 9a, which are on the outside of the layers 1a and 2a, said layers 1a and 2a being similar to the layers 1 and 2 which have been previously described.

A horn of this type provides the resistance to moisture of an all-metal horn, while making it possible to cheaply construct these horns and to lower their weight. Likewise, the undesirable resonance effect of thin metal sections is entirely eliminated.

It is not essential to protect the inner

surface of the wall of the horn, because the horn is so held as to prevent rain from falling into its interior.

I prefer to make the metal sections of zinc, aluminum or steel of 20-22 gauge, although I do not wish to be limited to any particular metal. Likewise, while I prefer to use metal, I do not wish to be limited to the use of metal, as any other rigid and waterproof material could be employed in place thereof.

The metal ring 6 which is located at the mouth of the bell of the horn is an important feature of the invention.

If the horn is made of fabric conforming to said United States Patent No. 1,501,032, the fabric may be impregnated with a water soluble filler, and it may have a surface coating of a suitable waterproof lacquer, varnish, or the like. The metal sections are made by spinning, and the cost of spinning is much reduced by the use of separate metal sections, since the cost of spinning a metal section of the type shown herein, depends upon the length thereof.

It will be noted that the improved horn has a composite wall which is made partially of metal and partially of non-metallic material. Likewise, the metallic material is laterally spaced from the inner surface of the wall of the horn, said metallic material being between the inner and outer surfaces of the wall of the horn, in the embodiments shown in Figs. 1-5 inclusive, and being located on the outside of the wall of the horn, in the embodiment shown in Fig. 6. I do not wish to exclude from the invention a horn which may have a metallic section or sections on its inner surface, but it is preferred to have the inner surface of the wall of the horn made of non-metallic and non-resonant material. A single metal section, of the full length of the horn, may be used. The metal sections are transversely continuous since they consist of flared tubes, so that they protect the horn against moisture.

I have shown the preferred embodiment of my invention, but it is clear that numerous changes and omissions could be made without departing from its spirit.

I claim:

1. A loud speaker horn having a composite wall which is made of non-metallic material capable of being deformed by moisture and of a plurality of transversely continuous metallic sections, said metallic sections being longitudinally spaced from each other, said metallic sections being also spaced from the inner surface of said wall, said horn also having an outer protective member around the adjacent ends of a pair of said sections.

2. A loud speaker horn having a composite wall which is made of non-metallic material capable of being deformed by moisture and of a plurality of transversely continuous

5 metallic sections, said metallic sections being longitudinally spaced from each other, said metallic sections being also spaced from the inner surface of said wall, the interior surface of the wall being composed wholly of non-metallic material, said horn also having an outer protective member around the adjacent ends of a pair of said sections.

10 3. A loud speaker horn having a composite wall which is made of non-metallic material capable of being deformed by moisture and of a plurality of transversely continuous metallic sections, said metallic sections being longitudinally spaced from each other, said metallic sections being also spaced from the inner surface of said wall, said metallic sections being located between the inner and outer surfaces of said wall.

15 4. A loud speaker horn having a composite wall which is made of non-metallic material capable of being deformed by moisture and of a plurality of transversely continuous metallic sections, said metallic sections being longitudinally spaced from each other, said metallic sections being also spaced from the inner surface of said wall, said metallic sections being located on the exterior surface of said wall, said horn also having an outer protective member around the adjacent ends 20 of a pair of said sections.

25 In testimony whereof I affix my signature.
30 ALEXANDER I. ABRAHAMS.
